UNITED STATES PATENT OFFICE.

JOHN L. WHITTEN AND J. HERMON WHITTEN, OF BURLINGTON, VERMONT.

IMPROVEMENT IN MITTENS.

Specification forming part of Letters Patent No. 150,270, dated April 28, 1874; application filed February 28, 1874.

CASE B.

To all whom it may concern:

Be it known that we, JOHN L. WHITTEN and J. HERMON WHITTEN, of Burlington, in the county of Chittenden and State of Vermont, have invented a new and useful Improvement in Mittens and Gloves, of which the following is a specification:

The object of this invention is to increase the durability and usefulness of mittens and gloves; and consists in the arrangement of the back and palm pieces, and the ball and back pieces of the thumb.

In the accompanying drawing, Figure 1 represents the patterns employed in cutting out the mittens, showing the front and back pieces, and the ball and back pieces of the thumb. Fig. 2 is a view of the mitten complete, showing the palm side.

This mitten is made of four pieces below the wrist, the pieces being put together as seen in Fig. 2.

Similar letters of reference indicate corresponding parts.

A is the palm. B is the back. C is the ball-piece of the thumb. D is the back piece of the thumb. E is a seam which starts at the point F at the wrist G and runs entirely around the hand and finger part of the mitten, and over the sides of the thumb to the wrist-piece, as seen at H. The ball-piece C of the thumb is attached by this seam to the back pieces B and D, and to the palm-piece by the seam I.

This seam I is carried down from the thumb toward the palm of the hand, so that it does not affect the crimping of the leather at the curve under the thumb, and is consequently not subjected to much wear, and does not rip or fail. It will be seen that the curve J (and consequently the crimp of the leather) is all in the ball-piece C. The seam I connects with the seam E at the point K. The opposite edge of the back piece D is attached to the back piece B by a short seam which runs from the ball-piece C to the wrist. This seam is not shown in the drawing. This improvement relates exclusively to the palm and back, (or part in the rear of the fingers,) and is of course as applicable to gloves as to mittens, and is more especially designed for mittens and gloves made of buckskin or leather.

Having thus described our invention, we claim as new and desire to secure by Letters Patent—

1. The patterns A, B, C, and D, as shown and described, for the purposes set forth.
2. As a new article of manufacture, a mitten made from the above-described patterns, substantially as set forth.

JOHN L. WHITTEN.
J. HERMON WHITTEN.
